HOLDER FOR PERFUME TESTING BLOTTERS

Pierre Magnin, 15 Ave. Mozart, Paris, France

Filed Mar. 7, 1961, Ser. No. 64,176

Term of patent 14 years

(Cl. D74—1)

Fig. 1

Fig. 3

FIG. 1 is a front elevational view of a holder for perfume testing blotters showing my new design, the back thereof being similar in appearance;

FIG. 2 is a side elevation of the same; and

FIG. 3 is a top plan view of the same.

I claim:

The ornamental design for a holder for perfume testing blotters, as shown and described.
